UNITED STATES PATENT OFFICE.

THOMAS RALPH DOUSE, OF CHATHAM, COUNTY OF KENT, ENGLAND.

ELECTRICAL FIRE-EXTINGUISHER.

SPECIFICATION forming part of Letters Patent No. 406,341, dated July 2, 1889.

Application filed December 19, 1888. Serial No. 294,074. (No model.) Patented in England August 9, 1888, No. 11,514.

To all whom it may concern:

Be it known that I, THOMAS RALPH DOUSE, a subject of the Queen of Great Britain, residing at 28 Clover street, Chatham, Kent 5 County, England, have invented new and useful Improvements in Fire-Extinguishers, (for which I have obtained a patent in Great Britain, No. 11,514, bearing date August 9, 1888,) of which the following is a specification.

This invention relates to that type of fire-extinguishers wherein an alkali-containing vessel is provided internally with an acid-bottle, to be broken so that the acid and 15 alkali mix and generate a fire-extinguishing gas that issues from the alkali-vessel by a nozzle or distributor.

The object of my invention is to avoid the employment of a movable striker or hammer, as ordinarily used for breaking the bottle, and to provide novel means for fracturing the bottle through the medium of an electric current and a detonator.

To such end my invention consists in the 25 novel combination of devices hereinafter described and claimed, reference being made to the accompanying drawings exhibiting my invention, in which—

Figure 1 is a broken side elevation of the 30 alkali-vessel, showing the acid-bottle and the detonator; Fig. 2, a sectional view of the acid-bottle; Fig. 3, a detail bottom plan view of the screw-cap of the alkali-vessel; Fig. 4, a side view of one of the gas-distributors or nozzles; Fig. 5, a sectional view of the same; and Fig. 6, a diagram illustrating the invention with the electric circuit and battery.

In order to enable those skilled in the art 40 to make and use my invention, I will now describe the same in detail, referring to the drawings, wherein—

The letter A indicates the alkali-containing vessel or tank suspended by the lugs b 45 from a beam c, or it may hang from the ceiling of a room in a dwelling-house, warehouse, or store. The vessel or tank A is provided at about its central upper part with a screw-aperture for the reception of a cap G, (shown

in section at Fig. 2,) to close the opening or 50 aperture. The inside of the screw-cap has a spring tongue or clip d, as seen in the bottom plan view of the cap at Fig. 3, the clip d being so shaped that the neck of the glass acid-containing bottle B can be pushed in between the prongs of the clip d for the suspension of the acid-bottle.

The mouth of the bottle B is hermetically sealed by a glass tube e, within which tube a detonator or explosive plug f is arranged, 60 this being suspended by conducting-wires g, by which, when the electric circuit is closed in any well-known manner, the force of the explosion causes the tube e and also the acid-bottle B to be broken and the acid to fall into 65 and mix with the alkali in the tank A for creating or generating a powerful fire-subduing gas. The gas thus formed escapes along with a portion of the liquid by the bent pipes D D, and issues in jet or spray-like 70 form from the perforations of distributors or nozzles, (see Figs. 4 and 5,) said nozzles E being on the exposed ends of the pipes D D for the distribution of the fire-extinguishing gas.

I surround the acid-bottle B by a wire-gauze net h, which is connected to the cap G, so that the fragments of the bottle can be 75 readily collected and a fresh bottle placed in the prongs of the clip d after recharging the tank with an alkali liquid to set the apparatus ready for use.

One apparatus would be sufficient for an ordinary-sized room; but for such as a warehouse or store and large floors several of 80 such apparatus may be fitted and be simultaneously discharged on the closing of the electric circuit by the pushing in of a button, the arrangement of which with three floors will be understood by the diagram, Fig. 6, 85 where a battery and electric circuit are exhibited.

Having thus described my invention, what I 90 claim is—

In an electrical fire-extinguisher, the combination of an alkali-containing vessel A, having tubes D projecting therefrom and provided on their exposed ends with spray-

nozzles E, a screw-cap G, inserted in the upper part of said vessel and provided with a clip d, an acid-containing bottle suspended from the clip d within said vessel, a tube e, extending into and sealing the bottle, a detonator f, placed in said tube, and an electric circuit including the detonator, substantially as described.

5 In witness whereof I have hereto signed my

name, in the presence of two subscribing witnesses, this 28th day of September, 1888.

THOMAS RALPH DOUSE.
